(57) **CLAIM**

The ornamental design for a tank trailer airfoil, as shown and described.

DESCRIPTION

FIG. 1 is a perspective upper view of a tank trailer airfoil; FIG. 2 is a perspective lower view thereof; FIG. 3 is a side elevation view thereof; FIG. 4 is a rear elevation view thereof; FIG. 5 is an isolated perspective upper view thereof; and, FIG. 6 is an isolated perspective lower view thereof.
